US0D1069844S

(12) **United States Design Patent** (10) **Patent No.:** **US D1,069,844 S**
(45) **Date of Patent:** **** Apr. 8, 2025**

(54) **COWLING FOR AN OUTBOARD MOTOR**

(71) Applicant: **Brunswick Corporation**, Mettawa, IL (US)

(72) Inventors: **John I. S. Park**, Fond du Lac, WI (US); **Todd D. Dannenberg**, Fond du Lac, WI (US); **Stephen R. Collins**, Fond du Lac, WI (US)

(73) Assignee: **Brunswick Corporation**, Mettawa, IL (US)

(**) Term: **15 Years**

(21) Appl. No.: **29/953,699**

(22) Filed: **Jul. 23, 2024**

Related U.S. Application Data

(62) Division of application No. 29/786,790, filed on Jun. 2, 2021, now Pat. No. Des. 1,042,542.

(51) **LOC (15) Cl.** **15-01**

(52) **U.S. Cl.** **D15/4**

(57) **CLAIM**

The ornamental design for a cowling for an outboard motor as shown and described.

DESCRIPTION

FIG. 1 is a front perspective view of a cowling for an outboard motor showing the design;

FIG. 2 is a rear perspective view thereof;

FIG. 3 is a side view thereof;

FIG. 4 is an opposite side view thereof;

FIG. 5 is a front view thereof;

FIG. 6 is a rear view thereof;

FIG. 7 is a top view thereof; and,

FIG. 8 is a bottom view thereof.

The broken lines in the drawings illustrate portions of the cowling for an outboard motor that are not part of the claimed design.

1 Claim, 8 Drawing Sheets
